UNITED STATES PATENT OFFICE

EDMUND C. MORGAN, DECEASED, LATE OF NEW YORK, N. Y., BY OLIVE EUGENIE MORGAN, EXECUTRIX, OF NEW YORK, N. Y.

MINING MACHINE

Original application filed June 7, 1920, Serial No. 387,137. Divided and this application filed September 28, 1927. Serial No. 222,479.

The invention relates to mining machines particularly adapted for mining coal, and one of its objects is the provision of breaking down mechanism combined with kerf-cutting mechanism to move into the kerf cut by the latter and operate in such kerf to break down the material.

A further object of the invention is the provision of breaking down mechanism combined with an upright shearing kerf-cutter to move into the kerf cut by the latter and operate in such kerf.

Another object of the invention is the provision of fluid-pressure breaking mechanism combined with kerf-cutting mechanism.

A further object of the invention is the provision of an expandible pressure-exerting device combined with a kerf-cutter to move into the kerf cut by the latter and exert pressure on the walls of the kerf.

Another object of the invention is the provision of pressure-exerting mechanism mounted on the kerf-cutter within the boundary thereof to move automatically with the kerf-cutter during the operation of the latter and to operate independently thereof.

Another object of the invention is the provision of pressure-exerting mechanism for collapsible kerf-cutting mechanism.

Other objects of the invention will appear hereinafter, the novel features and combinations being set forth in the appended claims.

This application is a division of co-pending application, Serial No. 387,137, filed June 35 7, 1920, granted November 22, 1927, No. 1,650,027, for an improvement in mining and loading machines.

In the accompanying drawings—

Fig. 1 is a plan view of an improved mining and loading machine;

Fig. 2 is an elevational view of the mining and loading machine with the uppermost parts folded into their lower positions and mounted on a mine car for transportation in a mine;

Fig. 3 is a sectional elevation on the line 3—3 of Fig. 1;

Fig. 4 is a sectional view of Fig. 1 on the line 4—4 looking in the direction of the arrows;

Fig. 5 is a sectional view on the line 5—5 of Fig. 1 looking in the direction of the arrows; and

Fig. 6 is a sectional elevation of Fig. 1 on the line 6—6 looking in the direction of the arrows.

Referring to Fig. 1, it will be seen that the mining and loading machine is mounted in a pan 7 which is rectangular in plan view and is provided with vertical side plates 8 and 9 which act as guideways for the main frame 10. The mechanism for sliding the main frame 10, together with the mining and loading mechanism mounted thereon, longitudinally along the pan, will be hereinafter described.

Secured to the sides of the frame 10, as shown in Fig. 5, are two electric motors 11 and 11' which are connected together to act in unison. These electric motors are located intermediate the ends of the machine, as shown in Fig. 1. It is preferred to use two electric motors at opposite sides of the machine so that each may occupy a comparatively low position and each may be made smaller than if one electric motor alone were used. In other words, by the use of two spaced-apart electric motors the required operating power may be secured while at the same time the height of the machine is materially reduced, thereby enabling the construction of a mining machine, or of a combined mining and loading machine, which requires little headroom and can therefore operate in mine chambers having comparatively low roofs.

The motor shaft 12 is provided with a bevel gear pinion 13 which meshes with a bevel gear 14 on the transverse shaft 15, as shown in Fig. 1. In the same manner the motor shaft 16 on the opposite side of the machine is provided with a bevel gear pinion 17 meshing with a bevel gear 18 on the transverse shaft 15. The latter is provided with a bevel pinion 19 which meshes with the horizontal bevel gear 20 loosely mounted on a vertical shaft 21; to the hub of the gear 20 to rotate therewith is secured the sprocket 22 in mesh with the chain kerf-cutter illustrated at 23 in Fig. 1. It will thus be seen that when the spaced-apart electric motors 11 and 11' are operated,

power will be transmitted to the undercutting chain cutter 23 to drive the same.

The undercutter comprising the cutter chain 23 is mounted on a cutter frame 24 5 detachably connected to the supporting framework so that when desired the frame 24 may be removed after two adjacent links of the chain 23 have been disconnected.

The cutter frame 24 may be supported from 10 the side pieces 25 and 26 by means of the bolts 27 and 28 extending through the slots 29 and 30 and provided with nuts 31 and 32, as shown in Fig. 1. In order to adjust the slack in the chain 23, the cutter frame 24 may 15 be moved forwardly or rearwardly after the nuts 31 and 32 have been loosened so that the bolts 27 and 28 may slide along the slots 29 and 30. This adjusting mechanism comprises a screw-threaded rod 33 threaded through 20 the rear end of the cutter frame 24, as shown in Fig. 3. The rod 33 is mounted in a bearing in the cross-piece 10' which is secured to the main frame 10. A collar 34 secured to the rod 33 holds the latter in the cross-frame 10' 25 so that when the bevel gear 35 on the rod 33 is rotated the cutter frame 24 may be moved forwardly or rearwardly relatively to the frame 10' and the main frame 10. The bevel gear 35 and consequently the rod 33 may be rotated 30 by means of a manually operated socket wrench applied at the squared end 36 of the shaft 37, there being a bevel gear 38 at the end of the shaft 37 in position to mesh with the bevel gear 35.

It should be understood that the parts designated 25 and 26 in Fig. 1 are rigidly connected to the main frame which is shown at 10 in Fig. 3. By referring to Fig. 6, which is a sectional view of Fig. 1 on the line 6—6 40 looking in the direction of the arrows, it will be seen that the cutter frame 24 is supported in a low position relatively to the positions of attachment of the upright side cutters to the main frame. In other words, the supports 45 25 and 26 shown in Fig. 1 are located in horizontal planes below the supports for the upright side kerf-cutters.

The upright side kerf-cutters 39 and 40 are each mounted on the main frame 10 for operation in upright position and for folding to the horizontal position shown in Fig. 2 during transportation of the mining and loading machine. Inasmuch as the means for connecting the upright side kerf-cutters to the 50 main frame is the same at both sides of the machine, the details of the supporting mechanism at one side only will be described and are as follows: Referring to Figs. 1 and 3 55 it will be seen that the upright side kerf-cutter comprises a cutter frame 41 for receiving the cutter chain 42 which is connected to the sprocket 43. The cutter frame 41 is mounted on the supporting frame 44, the rear end of which is provided with a rod 45 projecting through the bearing 46 which is rig-

idly secured to the frame 10. This rod 45 projects through the rear end of the bearing 46 and is adapted to receive a collar 47 which may be connected to the rod 45 by a pin 48 so that the cutter supporting frame 44 cannot be moved longitudinally relatively to the main frame 10 but may be turned to folded position on the axis of the rod 45. In order to hold the cutter supporting frame 44 in upright position a bolt 49 may be provided 70 to pass vertically through the supporting frame 44 and screw-threaded into the main frame 10. When the upright kerf-cutter is adjusted to operating position and held in adjusted position by the bolt 49 screw-threaded into the main frame 10, the clutch element 50 will be in alignment with the clutch element 51 so that when the latter is moved into engagement with the former, power may be transmitted through the shaft 52 carried 75 by the supporting frame 44. When the shaft 52 is rotated motion will be transmitted to the bevel gears 53 and 54 to rotate the sprocket wheel 43 and thus drive the sprocket chain 42. A housing may be provided for the 80 protection of the bevel gears 53 and 54. It will also be seen by referring to Fig. 1, that the clutch element 51 is mounted on a shaft 55 the rear end of which is provided with a bevel gear 56 meshing with a bevel gear 57 85 on the transverse shaft 15.

Therefore, when the spaced-apart side electric motors 11 and 11' are operated the undercutting chain cutter, as well as both of the upright side chain kerf-cutters, will be driven 100 simultaneously.

In order to advance the mining machine to effect rectilinear feeding movement of the undercutting kerf-cutter and the spaced-apart side kerf-cutters, a rope winding device is provided at 58 for exerting a pull on a rope 59, the free end of which is anchored at 60 to the inner face of the vertical side plate 9 of the pan 7.

As shown in Figs. 1 and 5, the transverse 110 shaft 15 is provided with a worm 61 which meshes with the worm gear 62 on the longitudinal shaft 63. The rear end of the latter is provided with a worm 64 which meshes with the worm gear 65, as shown in Figs. 1 115 and 4.

By referring to Fig. 4, it will be seen that the worm 65 is mounted on a vertical shaft 66 and that on the latter is also mounted the rope drum 58 for receiving the rope 59. Power may be transmitted from the worm gear 65 to the rope drum 58 by operating the friction clutch 67. Such operation of the clutch 67 may be effected by grasping the handle 68 and turning the pressure finger 69 120 in the bearing 70.

Limit stop mechanism for automatically limiting the forward feeding movement of the kerf-cutters may be arranged by providing the handle 68 with a lateral projection 71, 130

as shown in Fig. 4, in position to strike against the limit stop 72 on the forward portion of the vertical side plate 9 of the pan 7. Therefore, after the clutch 67 has been thrown in manually it may be left in applied position but when the kerf-cutting mechanism reaches the desired limit of its forward stroke, the limit stop 72 will effect an automatic release of the clutch 67 and thereby 10 automatically stop the forward feeding movement of the kerf-cutting mechanism.

In order to retract the kerf-cutting mechanism along the pan 7, another rope winding mechanism 73 is provided at the opposite side 15 of the machine as shown in Fig. 1, the free end of the rope 74 being adapted to be anchored at 75 to the inner face of the vertical plate 8 near the rear end of the latter. The mechanism for securing the forward feeding 20 movement may be geared so as to be slow in accordance with the feeding movement desired, whereas the retracting movement may be much more rapid in order to save time in restoring the machine to its initial position 25 in readiness for another cutting operation. The gearing for operating the rope winding mechanism 73 is similar to that already described in connection with the rope winding mechanism 58.

30 The rearward movement of the mining machine on the pan 7 may be automatically stopped by limit stop mechanism comprising a vertical hinged stop block 76 projecting upwardly from the side plate 8 at the rear 35 portion of the latter, as shown in Fig. 1, and in position to be engaged by the projection 77 of the lever for operating the clutch similar to that shown at 67 in Fig. 4 but controlling the winding drum 73.

40 Attached to the pan 7 and extending rearwardly therefrom are supports 78 and 79, as shown in Fig. 1. These supports are provided, respectively, with direction pulleys 80 and 81 for receiving the rope 74, the free end 45 of which is adapted to be anchored in suitable positions in the mine. By extending the rope 74 around the direction pulley 80 and anchoring the free end of the rope in the mine, the pan 7, together with the mining 50 and loading machine mounted thereon, may be slid laterally over the mine floor by operating the rope winding apparatus 73. In order to slide the apparatus in the opposite direction the rope 74 may be extended around the 55 pulleys 80 and 81, its free end anchored in the mine, and the rope winding mechanism 73 operated. By extending the rope 74 around pulleys 80 and 83 to an anchorage the machine may be slid back longitudinally.

60 When it is desired to pull the pan, together with the mining and loading machine thereon, onto the mine car 82 shown in Fig. 2, the rope 74 may be disconnected from its anchorage 75 and extended around the pulley 80 65 and thence around the pulley 83 which is

mounted centrally at the rear end of the main frame 10, the free end of the rope being anchored at 84, to the rear end of the truck 82. Now, upon operation of the rope-winding apparatus 73, the main frame will be pulled toward the truck, and by reason of the stop pins at 85 and 86 the pan 7 will be moved rearwardly with the main frame along the upper surface of the truck to the rear end thereof to the position shown in Fig. 2.

70 Mounted on the forward portion of the framework is a receiving conveyer 87 occupying a position in an approximately horizontal plane within the boundary of the forward portion of the undercutter and between the upright side cutters, as shown in Figs. 1 and 3. This conveyer comprises a frame 88 which is detachably mounted upon the main supporting framework in position to permit the driving sprockets 89, 89 to engage the 85 sprocket chains of the endless conveyer 90, as illustrated in Fig. 3. The conveyer extends upwardly on an incline from the forward horizontal receiving portion and has an upper horizontal delivery portion as shown in 90 Fig. 3, and the direction of rotation of the driving sprockets 89 is such as to provide for the slack portion of the conveyer to extend in advance of the driving sprockets 89, thereby 95 increasing the length of engagement of the driving sprockets with the sprocket chains and keeping taut the carrying portions of the conveyer, as well as that portion which extends from the rear end of the conveyer to the sprockets 89. Inasmuch as the space above 100 the conveyer 87 is entirely free and unobstructed this conveyer is entirely detachable and when in operating position it may be retained in place by its own weight resting on the main frame 10 at 91 and 92 and on the cutter frame 24 at 93.

105 The sprockets 89 are mounted on the transverse shaft 94, as shown in Figs. 1 and 3, and the latter is geared at 95 to an electric driving motor 96.

110 Pivottally connected to the rear end of the main frame 10 is a hopper 97. This hopper is mounted on the main frame 10 for swinging movement on an upright axis. A conveyer frame 98 extends rearwardly from the hopper, as shown in Fig. 3, and three parallel endless conveyers 99, 100 and 101 are mounted on the conveyer frame 98 for simultaneous operation by the electric motor 102 which is connected to the driving sprockets 103. The 115 parallel conveyers 99, 100 and 101 extend into the hopper 97 but the central conveyer 100 is longer than the conveyers 99 and 101 so as to extend farther forward, as shown at 104 in Fig. 1, so as to be in position to more readily 120 receive the cuttings from the conveyer 105 when the conveyer frame 98 occupies a longitudinal position in alinement with the conveyer 87. The rear end of the conveyer 87 extends over all three conveyers 99, 100 and 101. 125 130

However, even when the conveyer frame 98 is swung from one side to the other, the hopper 97 will maintain delivery communication between the conveyer 87 and the rear swinging multiple conveyer.

5 The slack conveyer or the conveyer for receiving the cuttings from the undercutter is detachably mounted on an inclined intermediate portion of the frame 10. The slack conveyer may be self-contained and detachably mounted on the incline so that when the conveyer 88 is tipped up or removed the slack conveyer may be removed in its entirety.

10 The slack conveyer comprises an endless chain provided with flights movable over a plate 106 on which is mounted an electric motor 107 connected by the gearing 108, 109 and 110 to the sprocket 111 for driving the chain of the conveyer 105. Provision may be made, 15 as shown at 112, for regulating the tension of the chain of the conveyer 105.

15 From the foregoing it will be seen that while the two spaced-apart side motors 11 and 11' are relied upon to transmit power to the undercutter, to the side cutters and to the rope drums 58 and 73, separate motors are used for operating the conveyers, one for operating the conveyer 87, another for operating the conveyer 105, and still another for operating the 20 rear swinging multiple conveyer. These various motors may be separately controlled and operated in a well-known manner.

25 Each of the upright side kerf-cutters may be provided with hydraulic breaking devices 113 and 114 connected by means of pipes to pumps which are operated by eccentrics on the transverse shaft 15. Inasmuch as the pumping mechanism and the connections between the same and the hydraulic breakers 30 are the same for both of the upright side kerf-cutters, a description of the mechanism located at one side will be sufficient. Referring to Fig. 1, an eccentric is shown at 115 for operating a pump 116 connected by 35 means of the pipe 117 extending through the supporting frame 44, to the pipe 118 shown in Fig. 3.

40 If desired the pumps 116 may be pneumatic and the transmission of fluid therefrom to the breakers controlled by a valve 119 shown in Fig. 1. Therefore, the pumps may run idly during the operation of the undercutter and the side cutters until it is desired to effect the operation of the fluid 45 pressure breakers 113 and 114. Then the valves 119 may be operated to direct the fluid pressure from the pumps to the fluid pressure breakers to effect relative expansion of the two parts 120 and 121 shown in Fig. 6. 50 The part 120 will then press against the wall of the unmined mass and the part 121 will effect breaking down of the coal between the side cutters and above the undercutter. A contractile spring 122 is provided between the 55 parts 120 and 121 to restore the same to their

initial positions by drawing them together when the fluid pressure is released.

60 In some instances the nature of the coal is such that the fluid pressure breakers 113 and 114 will be sufficient to break down the coal in pieces of such sizes as are capable of being handled by the conveyer 87, but when desired the breaking of the coal may be assisted by means of the operation of one or more pick machines mounted on the frames of the 65 motors 11 and 11'. Such pick machines are also useful to trim off the roof or to complete the mining of the coal vein and to provide sufficient clearance for continued passage of the machine into the mine.

70 As shown in Fig. 5, the upper sides of the frames of the motors 11, 11' are provided with longitudinal inverted T-shaped grooves 123 and 124 to receive a dove-tailed connection of the support 125 which is connected by a universal joint 126 to the frame 127 of the pick machine.

75 The pick machine is provided with operating handles 128 by means of which the direction and operation of the pick machine may be controlled. Such pick machine is preferably of the reciprocatory type and may be slid along the guideways 123 and 124 independently of each other and driven by compressed air through the pipes 129 in any 80 position to which the pick machine is adjusted. By reason of the adjustment forwardly and rearwardly along the guide grooves 123 and 124 and by reason of the universal joint 126 the pick machines may 85 each be used to command a large area of the mine wall or of the cut material between the side cutters and above the undercutter, as well as at the roof above the range of operation of the side cutters.

90 By comparing Fig. 3 with Fig. 2, it will be seen that when the pick machine is in position to slide along the groove 123 it occupies an elevated position in planes above the conveyer 87. Therefore, when the picks are 95 operated they may command a wide area at the mine wall without interfering with the operation of the conveyer. The rear ends of the guideways 123 and 124 are provided with pivoted sections illustrated at 130 in Fig. 2. This rear section is pivoted at 131 so that it 100 may occupy a downwardly inclined position after the support 125 has been moved into the extension 130. In other words, by the provision of the rear pivoted section 130 the pick machine may be moved into this pivoted section and then let down into a lower or folded position where it will fit between the motor frame and the conveyer 87. The pick machine frame 127 may be provided with a 105 forwardly extending angle-iron frame 132 for receiving the plunger rod 133 of the pick and therefore when the pick machines are lowered to their folded positions these angle-iron frames 132 and the rods 133 will occupy 110

105

110

115

120

125

130

the positions illustrated in Fig. 5 between the frames of the motors 11 and 11' and the conveyer 87. It will thus be seen by reference to Figs. 2 and 5, that when the pick machines are in their lower or folded positions they are approximately level with the upper surface of the frames of the motors 11 and 11' and also approximately at the same elevation as the rear upper horizontal portion of the conveyer 87. This folding feature of the pick machines is particularly desirable during transportation of the mining and loading machine on a mine car from one part of the mine to another.

The upright side cutters may also be folded to lower positions during transportation by loosening the bolts 49 and turning the side cutters on the pivot pins 45. This is illustrated at the right-hand portion of Fig. 6. It should be understood that both of the side cutters may be moved to such folded position and occupy such space as to afford approximately the same headroom as is afforded when the pick machines are folded to their lower positions. Fig. 2 represents both of the side cutters and the pick machines folded to their lower positions so as to reduce the height of the mining and loading machine to a minimum, thus making provision for transportation on a mine car through very low roof mine chambers.

It should be particularly noted that all of the operating parts of the mining and loading machine hereinbefore described, and as shown on the drawings, are symmetrically arranged so as to well balance the operating parts and the weights thereof as well as the weight of the entire mining and loading machine. This is true not only with respect to the side cutters and the parts mounted thereon and connected thereto, but also with respect to the spaced-apart side motors 11 and 11', the rope winding devices and the slack conveyer which is centrally located. It should also be observed that two guide grooves 123 and 124 are provided, one on top of each of the motors 11 and 11', so that when two pick machines are employed one on each side of the machine, the weights due to the pick machines will also maintain balanced weight of the entire machine and its operating parts.

The hinge stop block 76 is preferably mounted on the upper portion of the side plate 8 to swing on a longitudinal axis 134, as shown in Fig. 4, so that when desired this stop block may be manually grasped and moved laterally out of the way of the projection 77, thus permitting the application of the friction clutch of the rope winding mechanism 73 to effect the operation of the latter when desired. After the mining and loading machine has been moved rearwardly along the pan 7 and automatically stopped by the stop motion mechanism comprising

the parts 76 and 77, it may be desired to extend the rope 74 to anchorages in the mine as hereinbefore described so as to shift the pan 7 together with the mining and loading machine thereon, to a desired location. By providing a hinge for the stop device 76 the clutch for the rope winding mechanism 73 may be applied without first moving the mining and loading machine forwardly along the pan 7, because as soon as the stop 76 is moved laterally, it is freed from the projection 77 and the clutch may then be applied.

It should also be noted that the space below the slack conveyor 105 may be provided with a closed compartment 135 for receiving compressed air for operating the pick machines. The compressed air stored in the compartment 135 may be conveyed to the pick machines through the outlet pipe 129' and the flexible pipe 129. The use of this compartment 135 for the storage of compressed air for operating the pick machines, does not interfere with the arrangement or operation of the other parts of the mining and loading machine. It is preferable to use the compartment 135 for such purpose to secure compactness and economy of available space.

By referring to Fig. 6, it will be seen that the cylinder 120 and plunger 121 are so mounted in the cutter frame 41 as to be both movable relatively thereto. By operating the valve 119 of Fig. 1 to introduce a limited amount of compressed air into the cylinder 120, the pressure-exerting device will be expanded only to a limited degree in which event the expansion will be insufficient to break down the material but will act only to keep the walls of the kerf spaced apart. That is to say, when the pressure-exerting device is operated only to a limited extent, it will act as a spacer to yieldingly hold the kerf open and prevent the kerf-cutter from binding in the kerf.

It should also be noted that when the valve 119 is operated to connect the air pump 116 to the pneumatic breaker 113 or 114, the latter will expand and can act to break down the coal independently of the feed of the machine. That is, whether the machine is being fed or not, the breakers may be operated.

By having a separate valve 119 at each side of the machine, the breakers may be caused to operate individually and independently of each other. When a body of coal has been undercut and sheared by the spaced-apart side cuts, the breakers may be operated alternately to secure a prying action on the coal and thus facilitate its being cracked considerably before being broken down. By this alternate operation the coal may be broken down more efficiently for handling by the conveyor 87.

Obviously those skilled in the art may make various changes in the details and ar-

rangement of parts without departing from the spirit and scope of the invention as defined by the claims hereto appended, and I desire therefore not to be restricted to the precise construction herein disclosed.

5 Having thus shown and described an embodiment of this invention, what I claim and desire to secure by Letters Patent of the United States is:—

10 1. In a mining machine, the combination with a supporting frame, of an undercutting kerf-cutter mounted on the forward end thereof, an upright shearing kerf-cutter, means for mounting said upright shearing kerf-cutter for adjustment to a horizontal position in folding relation to said under cutter for transportation, a fluid pressure breaking device mounted on the shearing kerf-cutter, power transmission mechanism 15 for operating said undercutter and said shearing kerf-cutter, and means associated with said power transmission mechanism for operating said fluid pressure breaking device when said shearing kerf-cutter is in upright operative position.

20 2. In a mining machine, the combination with a supporting frame, of an upright kerf-cutter mounted thereon, means for supporting said kerf-cutter in folded relation to said frame, a fluid pressure breaker on said kerf-cutter, and means for operating said breaker when said kerf-cutter is in upright position.

25 3. In a mining machine, the combination with a supporting frame, of an undercutting kerf-cutter mounted on the forward end thereof, an upright shearing kerf-cutter comprising a cutter frame, means for supporting said shearing kerf-cutter for a tilting movement to a folded relation with said under cutter and said supporting frame, expandible pressure exerting mechanism carried by said shearing kerf-cutter and movable bodily therewith to its folded position, power transmission mechanism between said supporting frame and said shearing kerf-cutter to drive the latter when in upright position, and means for operating said pressure exerting mechanism in the kerf produced by said 30 shearing kerf-cutter.

40 4. In a mining machine, the combination with a main frame, of an upright kerf-cutter, means for driving said kerf-cutter, mechanism for supporting said kerf-cutter in upright position relative to said main frame during operation of said kerf-cutter and for permitting the folding of said kerf-cutter on a longitudinal axis parallel to the center line of the machine but spaced laterally therefrom so that said kerf-cutter may occupy a relatively low position when out of operation without disconnecting said kerf-cutter from said frame, a breaker carried by said kerf-cutter and bodily movable therewith to 45 folded position, and means on said main

frame connected to said breaker to operate the same when the kerf-cutter is in operative position.

5. In a mining machine, the combination with a supporting frame, of an upright kerf-cutter comprising a cutter frame, means for pivotally connecting said cutter frame to said supporting frame for movement relatively thereto on a longitudinal axis extending lengthwise of the machine to permit movement of said kerf-cutter to a low folded position, means for securing said cutter frame to said main frame to occupy an upright position while in operation, a fluid pressure breaker carried by said cutter frame for movement into the kerf cut by said kerf-cutter, and means for operating said breaker in such kerf to break down the material adjacent the kerf-cutter.

6. In a mining machine, the combination with a main frame, of spaced-apart side kerf-cutters each pivotally connected to said main frame to swing relatively thereto on longitudinal parallel axes from upright position to approximately horizontal folded position, a breaker on each kerf-cutter in position to act in the kerf cut thereby to break down the cut material, means for operating said kerf-cutters when in upright position, and mechanism for operating said breakers in said kerfs.

7. In a mining machine, the combination with a supporting frame, of a kerf-cutter mounted thereon, a pneumatic breaker carried on said kerf-cutter, and an air pump connected to said breaker to operate the same.

8. In a mining machine, the combination with a supporting frame, of a kerf-cutter mounted thereon, an expandible pressure-exerting device carried by said kerf-cutter, and pneumatic means for operating said device to a limited extent to cause it to act as a yielding spacer in the kerf cut by said kerf-cutter.

9. In a mining machine, the combination with a supporting frame, of a kerf-cutter mounted thereon, an expandible pneumatic breaker on said kerf-cutter, a pump for supplying compressed air to said breaker, and a valve for connecting the pump to the breaker to effect the operation of the latter at will.

10. In a mining machine, the combination with a plane kerf-cutter comprising a cutter chain, of a flat fluid pressure breaker on said kerf-cutter within the boundary of said cutter-chain, means for operating said kerf-cutter including the feed thereof, means for operating said fluid pressure breaker at will independently of the feed of said kerf cutter, and connections for supporting the kerf-cutters in folded relation for transportation in the mine.

11. In a mining machine, the combination with a supporting frame, of a plane kerf-cutter mounted thereon, a fluid pressure breaker on said kerf-cutter, means for supporting

- 5 said kerf-cutter in an upright operating position and in a low-down folded position, a source of fluid pressure on said frame, and connections between such source and said breaker maintained for the various positions of said kerf-cutter.
- 10 12. In a mining machine, the combination with a supporting frame, of a kerf-cutter mounted thereon, means for supporting said kerf-cutter in vertical and horizontal positions, and an expansible breaker carried by said kerf-cutter in position to move into the kerf cut thereby and operable to break down the material independently of the feed of said kerf-cutter.
- 15 13. In a mining machine, the combination with a supporting frame, of a kerf-cutter mounted thereon for folding movement toward a horizontal position, and an expansible breaker on said kerf-cutter mounted for movement from a higher to a lower elevation when said kerf-cutter is thus folded and operable independently of the feed of the kerf-cutter to break down material when said kerf-cutter is upright.
- 20 14. In a mining machine, the combination with a supporting frame, of a kerf-cutter mounted thereon, an expansible breaker on said kerf-cutter in position to break down material, means for feeding said kerf-cutter while said breaker is released and free to move along the kerf cut by the kerf-cutter, and means for supporting said kerf-cutter for adjustment with said breaker on an axis 25 extending longitudinally of said frame to positions in varying planes.
- 25 15. In a mining machine, the combination with a supporting frame, of an undercutting kerf-cutter, an upright kerf-cutter, a hinged connection between said upright kerf-cutter and said supporting frame, and an expansible pressure exerting device on the upright kerf-cutter in position to move into and along the kerf cut by the latter.
- 30 45 16. In a mining machine, the combination with a supporting frame, of an undercutting kerf-cutter, spaced-apart upright kerf-cutters, hinged connections between said upright kerf-cutters and said supporting frame, and 50 expansible pressure exerting devices one on each of said upright kerf-cutters in position to move into and along the kerfs cut by the latter.
- 35 55 17. In a mining machine, the combination with a supporting frame, of an undercutting kerf-cutter, an upright kerf-cutter, a hinged connection between said upright kerf-cutter and said supporting frame to enable said upright kerf-cutter to be swung on a pivot 60 extending longitudinally of the length of the machine, and pressure exerting mechanism mounted on said upright kerf-cutter in position to have all portions thereof enter the kerf cut by said upright kerf-cutter in 65 advance of the rear end of said kerf.
18. In a mining and loading machine, the combination with a supporting frame, of an undercutting kerf-cutter mounted thereon, upright spaced-apart kerf-cutters at the sides of said undercutting kerf-cutter, mechanism for supporting said kerf-cutters for folding thereof on longitudinal axes parallel to the longitudinal length of the machine, means for securely holding said upright kerf-cutters in upright kerf-cutting positions, fluid pressure breakers on said upright kerf-cutters, loading apparatus extending rearwardly from said undercutter and between said upright kerf-cutters, and means for operating said breakers in the kerfs cut by said upright kerf-cutters to break down the mineral onto the forward end portion of said loading apparatus.

- In testimony whereof I have signed my name to this specification on this 24th day of September, A. D. 1927.
- OLIVE EUGENIE MORGAN,
Executrix of Edmund C. Morgan, Deceased.
